[57] CLAIM

The ornamental design for a combined personal cooler and seat, as shown and described.

DESCRIPTION

FIG. 1 is a perspective view of the combined personal cooler and seat showing my new design;

FIG. 2 is a top plan view thereof;

FIG. 3 is a bottom plan view thereof;

FIG. 4 is a front elevational view thereof;

FIG. 5 is a side elevational view thereof;

FIG. 6 is a cross-sectional view taken along line 6—6 of FIG. 5;

FIG. 7 is a perspective view of an alternate embodiment of FIG. 1;

FIG. 8 is a top plan view of FIG. 7;

FIG. 9 is a bottom plan view of FIG. 7; and

FIG. 10 is a side elevational view of FIG. 7.
